William J. Freihofer,
Inventor:

UNITED STATES PATENT OFFICE.

WILLIAM J. FREIHOFER, OF PHILADELPHIA, PENNSYLVANIA.

DESIGN FOR A SHEET OF WRAPPING PAPER.

Application filed February 26, 1923. Serial No. 5,270. Term of patent 14 years.

To all whom it may concern:

I, WILLIAM J. FREIHOFER, a citizen of the United States, residing in the city of Philadelphia, county of Philadelphia, and State of Pennsylvania, have invented a new, original, and ornamental Design for a Sheet of Wrapping Paper, of which the following is a specification, reference being had to the accompanying drawing, forming part thereof.

The figure is a plan view of a sheet of wrapping paper showing my new design.

I claim:

The ornamental design for a sheet of wrapping paper substantially as shown.

WILLIAM J. FREIHOFER.
